BRAKE HANGER

Frederic Schaefer, Pittsburgh, Pa.

Original application March 12, 1930, Serial No. 435,266. Divided and this application September 7, 1932. Serial No. 631,975

4 Claims. (Cl. 183—209)

The invention relates to hangers for suspending brake beams from the trucks of railway cars, coaches, and the like, and is a division of application Serial No. 435,266, filed by Frederic Schaefer, 5 March 12, 1930, having to do particularly with hangers provided with yokes having bearing surfaces especially adapted to uniformly resist the wear to which they are subjected in service.

The general type of brake hanger here contemplated as most commonly manufactured in the past is disclosed in United States Patent Nos. 1,385,851 to J. M. Summers, and 1,470,121 to Frederic Schaefer. As illustrated in those patents the yokes of the hangers are formed some- 15 what in the shape of I-beams, having upper and lower sides which are rounded, adapting them to act as bearing surfaces for the brake beams which they support. The upper or main of these bearing surfaces has the burden of supporting the 20 brake beam practically continuously, the exception being when the brakes are applied while the wheels are rotating in a direction tending to raise the brake beam and thereby cause it to bear against the lower or secondary surface. As a 25 result, the upper bearing surface, as shown in Patent No. 1,470,121 is preferably made with a greater wearing area than the lower.

The most economical way to manufacture hangers of this character is to form them from 30 simple rolled stock having uniform cross-section, and preferably from cylindrical rods. Such rods, in accordance with the prior practice, were first cut to the desired length. Next, the ends thereof were upset and the eyes for receiving their supporting pins were then formed in them and the rods then bent to the shape of the finished hanger. Thereafter the yoke portions of the hangers were forged to provide them with bearing surfaces of 35 unequal areas as desired, and usually with a 40 cross-sectional shape substantially that of an I-beam.

In forging such shapes mating dies are usually used and in the forging operation a considerable amount of metal is squeezed out in the form of a 45 flash between the dies, and at the same time the yoke metal gives longitudinally, all of which tends to reduce the cross-section of the yoke. Not infrequently the cross-sectional area of the yoke, by reason of this flash which must be removed and 50 the longitudinal flow of the metals is reduced as much as from 12 to 15 percent of the area started with. Hence, in order to provide a hanger with a yoke having a cross-sectional area at least equal to that of its side arms, it is necessary to upset 55 the yoke portion of the hangers enough before

they are forged to compensate for the flash loss and the longitudinal flow of metal accompanying the forging operation. This, of course, along with the time necessitated for the removal of the flashes, together with the metal lost in the flashes, 60 adds to the cost of the hangers.

A further problem encountered in hangers having a yoke portion of I-beam cross-section is that it often happens that the yoke becomes bent 65 slightly during the flash-trimming operation, which throws the hanger out of line and tends to weaken it. In addition, the pronounced change in shape between the side arms and yokes of such hangers tends to weaken them.

A further difficulty in the manufacture of 70 hangers having the old I-beam type of yoke is that after the cylindrical rods from which they are formed are bent into the shape of a hanger, considerable stoving of the metal towards the corners or bends is required in order to fill the 75 forging dies. This necessitates the hanger blank being heated to a high temperature to obtain sufficient plasticity of the metal to permit it to flow in the dies, this being undesirable as it tends to produce enlarged grain structure which weakens 80 the hanger. Furthermore, the intense heat at which a furnace in which the hangers are heated must be operated in order to be commercially feasible produces a severe shock on the 85 metal if the hangers are charged cold, as is the usual practice. Also where a blank is heat treated after it has been drop-forged, if it has thin portions in it, such as the thin web portions of 90 yokes of the aforementioned type of hanger, the unequal heating and cooling of the metal in the different portions of the hanger tend to produce an uneven grain structure that in turn sets up enormous internal strains which it is most important to guard against.

With the foregoing in mind, it is an object of 95 this invention to provide a brake hanger having side arms and a yoke all having substantially the same cross-sectional areas throughout, the yoke having bearing surfaces of unequal areas which are proportioned in accordance with the loads 100 they must carry in service, whereby to reduce the bearing wear of the hanger to a minimum.

Another object is to provide a hanger of this character having a yoke which may be shaped 105 quickly, easily and without loss of metal or strength when formed.

A further object is to provide a hanger in which the bends are not weakened by reason of the cross-sectional contour of the yoke.

The invention is illustrated in the accompany- 110

ing drawing, of which Fig. 1 is a face view of a U-type of brake hanger having a yoke formed according to this invention; Fig. 2 a side view thereof; Fig. 3 a cross-section of the yoke on line 5 III—III of Fig. 1; Fig. 4 a cross-section of the corner portion taken on the line IV—IV of Fig. 1; and Fig. 5 a cross-section of a leg.

Referring to the embodiment of the invention illustrated in the drawing, there is shown a U-shape brake hanger comprising side arms 1 and an integral suspension type of yoke 2. In the upper ends of these side arms there are provided the usual eyes 3 which are provided for receiving the pins by which the hanger is connected to the 10 truck frame. As shown in Fig. 5, the side arms are preferably circular in cross-section, and, as shown in Fig. 3, the yoke 2 is provided with an upper arcuate main bearing surface 4 and a lower arcuate secondary bearing surface 5, the area of 15 the former surface being materially greater than that of the latter, and the two proportioned in accordance with the load which they encounter. To increase the strength of the yoke and simplify its formation, as well as minimize the internal 20 strains set up in it when it is heat treated, its lateral sides 6 are made substantially plane and converge towards each other from the edges of the main to the edges of the secondary bearing surface. The yoke when so formed is also elongate in cross-section, that is, pear-shape, which 25 gives it greater shear resisting strength and permits it to be interlocked with a brake beam in a well known manner.

In the manufacture of such a hanger from a 30 cylindrical rod of equal cross-sectional area, the rod is first cut to length and upset at its ends in the usual way to form widened portions through which holes are drilled to form eyes 3. The rod is then bent into U-shape, and the cylindrical 35 yoke-forming portion placed between a pair of plane converging dies by which it is pressed into yoke 2 having the cross-sectional form shown in Fig. 3. The ends of the dies are so shaped as to 40 form strengthening ribs 7 at the outside of the bends of the hanger, the ribs gradually merging at their ends into the yoke and side arms 1.

When so produced, no upsetting of the yoke-forming portion is required as flashes are eliminated and there is substantially no elongation of 45 the yoke, and the cost of manufacture is materially reduced.

Furthermore, a yoke may be formed in this manner without heating it to as high a temperature as is necessary in forming the old type yokes, 50 because the deformation to which the stock must be subjected is comparatively small and less plasticity of the metal is required. This also tends toward the production of a finer grain structure, and as there are no thin portions in a yoke of 55 pyriform, the grain structure remains uniform throughout the yoke during the heat-treatment and oil-quenching processes; hence internal stresses are minimized and the overall strength materially improved.

5

What has been said hereinbefore with respect to U-shaped hangers will be appreciated by those skilled in the art as also applying to loop type hangers which differ from the described hangers only in the use of an upper supporting yoke in 80 place of the eye and pin type of suspension.

According to the provisions of the patent statutes, I have explained the principle of my invention, and have illustrated and described what I now consider to represent its best embodiment. However, I desire to have it understood that, within the scope of the appended claims, the invention may be practiced otherwise than as 85 specifically illustrated and described.

I claim:

1. A brake hanger having side arms and an integral transverse yoke, the yoke and side arms being of substantially equal cross-sectional area throughout, and the yoke having arcuate main and secondary bearing surfaces of large and small 90 areas, respectively, and having substantially plane-faced converging sides joining the edges of said main and secondary bearing surfaces.

2. A brake hanger having side arms and an integral transverse yoke of elongate cross-section, 100 the yoke and side arms being of substantially equal cross-sectional area throughout, the yoke having a main inner load-carrying arcuate bearing surface of relatively large area, an outer secondary arcuate bearing surface of comparatively 105 small area, and having substantially plane-faced converging sides joining the edges of said larger and smaller bearing surfaces.

3. A brake hanger having side arms and an integral transverse yoke of elongate cross-section, 110 the yoke and side arms being of substantially equal cross-sectional area throughout, the yoke having a main inner load-carrying arcuate bearing surface of relatively large area, an outer secondary arcuate bearing surface of comparatively 115 small area, and having substantially plane-faced converging sides joining the edges of said larger and smaller bearing surfaces, and a strengthening rib extending outward from the yoke at each 120 end of the secondary bearing surface and around the outside of a bend of the hanger and merging with a side arm.

4. A brake hanger having side arms and an integral transverse yoke of elongate cross-section, 125 the yoke and side arms being of substantially equal cross-sectional area throughout, the yoke having a main inner load-carrying arcuate bearing surface of relatively large area, an outer secondary arcuate bearing surface of comparatively 130 small area, and having substantially plane-faced converging sides joining the edges of said larger and smaller bearing surfaces, and a strengthening rib extending outward from the yoke at each end of the secondary bearing surface and around the outside of a bend of the hanger and merging 135 with a side arm, the cross-sectional contour of said yoke gradually merging at each end into that of said side arms.

FREDERIC SCHAEFER.
